PLAY PEN

Axel W. Swanson, Chicago, Ill., assignor to Holmquist-Swanson Company, a corporation of Illinois

Application May 2, 1936, Serial No. 77,577

2 Claims. (Cl. 5—99)

- This invention relates particularly to play pens and more particularly to a portable pen which may be folded up readily so as to occupy but a small amount of space when not in use.
- 5 The primary object of the invention is to provide an improved pen having folded side walls which may be locked in the open position by means of a simple latch which is easy to operate but cannot be readily opened by a child.
- 10 A further object of the invention is to provide a play pen with a floor which is disposed somewhat above the floor of the room by means of rigidly connected central legs and is also supported by a tongue and socket connection with
- 15 the side walls of the pen.

The invention is illustrated in a preferred embodiment in the accompanying drawings, in which—

Fig. 1 is a plan view of a pen embodying the invention; Fig. 2 is a plan view showing the device in its partially folded position; Fig. 3, a side elevational view of the same; Fig. 4, a broken sectional view taken as indicated at line 4 of Fig. 3; Fig. 5, a broken sectional view taken as indicated at line 5 of Fig. 3; Fig. 6, a detailed sectional view taken as indicated at line 6 of Fig. 1; Fig. 7, a broken sectional view showing the floor support taken as indicated at line 7 of Fig. 1; and Fig. 8, a broken sectional view taken as indicated at line 8 of Fig. 2.

In the embodiment illustrated, A designates rigid side walls to which are pivotally connected, at each end, jointed side walls A'; B, a pair of floor sections provided with legs B'; and C, latching means for holding the jointed sections A' in extended position.

The side walls A are of conventional construction, having posts 9 provided with upper and lower cross bars 10 between which may be fitted 40 suitable rungs 11. The jointed side walls A' are similar in construction to the side walls described above, but are pivotally connected at their central portion by means of hinges 12. These jointed sections are pivotally connected to the 45 side walls A by means of corner hinges 13, see Fig. 4. The centers of the hinges are so placed as to permit the floor sections B to be snugly embraced by the sections A' when the device is in collapsed position.

50 The floor sections B are hinged to the lower portions of the side walls A by means of hinges 14. In order to keep the sections well above the floor and protect the occupant from floor drafts, the slats 15 are nailed to cross bars 16 which in 55 turn, are supported at the central portion of

the pen by means of the legs B'. These legs are fixed to the cross bars of one section by means of a pair of L-shaped brackets 17 which are spaced apart so as to provide a socket to receive the ends of the cross bars of the opposite section, as indicated in Fig. 6. The central cross bars are provided at their outer ends with dowel pins 18 which are adapted to swing down into sockets 19 provided in the lower cross bars 10 of the side walls A. Thus, it will be 10 understood, that each floor section is supported at six different points.

The latching member C is disposed on the inside of the jointed side walls A' and comprises a leaf spring 20 which may be rigidly connected 15 to one of the sections by means of rivets 21 which also serve to hold the upper hinges 12 in position. The free end of the leaf spring is provided with a perforation 22 which is adapted to snap over a stud 23 provided on the inner end 20 of the rivet or fastener 24. A push button 25 is provided with a shank 26 which extends through one leg of the hinges 12 and through the wall section A' into contact with the spring 20. A portion of the opening in the section A' is 25 counterbored, as indicated at 27, to permit limited movement of the collar 28 therein.

As shown in Fig. 8, the upper ends of the floor sections B are provided with a leather strap 29 by which the section may be fastened to one 30 of the rungs 11 while the device is being folded up.

As will be readily understood, when it is desired to fold up the device, the floor sections B are turned upwardly and latched, as indicated in 35 Fig. 8. The operator may then reach out and simultaneously depress both of the push buttons 25 which will cause the latches 20 to be released from the studs 23 and the sections A' may then be swung inwardly as shown in Fig. 2. From this 40 position, the side walls A may be drawn closely together and the play pen will be collapsed so as to occupy a very small amount of space and be readily portable. In the open position illustrated in Fig. 1 the upper sections of the jointed 45 walls A' are held in extended position by the locks C and the lower portions are held extended by the floor sections B.

The foregoing detailed description has been given for clearness of understanding only, and 50 no unnecessary limitations should be understood therefrom, but the appended claims should be construed as broadly as permissible, in view of the prior art.

I claim:

1. A portable play pen comprising: a pair of rigid opposed side walls; a pair of centrally jointed side walls connecting adjacent ends of the first mentioned side walls by means of end hinges, said central joints being arranged so as to swing inwardly into the enclosure; latches for holding the upper portion of the jointed walls in extended position; push-button means for releasing said latches; and a pair of floor sections hinged to said rigid side walls so as to swing upwardly into a plane parallel to said side walls, 5 and spaced to provide notches to receive the cross bars of the other floor section.
- 10 2. A portable play pen comprising: a pair of rigid opposed side walls; a pair of centrally jointed side walls connecting adjacent ends of the first mentioned side walls by means of end hinges, said central joints being arranged so as to swing inwardly into the enclosure; latches for holding the upper portion of the jointed walls in extended position; a pair of floor sections hinged to said rigid side walls so as to swing upwardly into a plane parallel to said side walls; and cross bars for each of said sections, the cross bars of 10 one section each carrying a central leg provided with a socket to receive the end of the cross bar of the opposite section, and a cross bar on each section provided with an extension adapted to swing down into a supporting socket provided in 15 the adjacent side wall.

AXEL W. SWANSON.
